UNITED STATES PATENT OFFICE.

DANIEL N. CALKINS, OF ROCHESTER, NEW YORK, ASSIGNOR TO ROCHESTER
GERMICIDE CO., OF SAME PLACE.

DISINFECTANT-HOLDER.

SPECIFICATION forming part of Letters Patent No. 681,100, dated August 20, 1901.

Application filed September 15, 1900. Serial No. 30,143. (No model.)

To all whom it may concern:

Be it known that I, DANIEL N. CALKINS, a citizen of the United States, residing at Rochester, in the county of Monroe, in the State of New York, (whose post-office address is 162 South avenue, Rochester, New York,) have invented certain Improvements in Disinfectant-Holders, of which the following is a specification, reference being had to the accompanying drawings.

My invention relates to certain improvements in disinfectant-holders, which improvements are fully described and illustrated in the following specification and the accompanying drawings, the novel features thereof being specified in the claims annexed to the said specification.

In the accompanying drawings, Figure 1 is a front view. Fig. 2 is a side view. Fig. 3 is a central vertical section. Fig. 4 is a plan view of the cup detached. Fig. 5 represents the same with the absorptive material and the siphon. Fig. 6 is a front view of the lower part of the inverted receptacle, the cup, and the siphon. Fig. 7 is a side view of the same. Fig. 8 is a side view of the same with the siphon arranged to feed into the delivery-tube.

In the accompanying drawings, A represents the body or fixed part of my improved disinfectant-holder; B, the detachable casing or cover; C, the inverted liquid-receptacle; D, the cup; F, the siphon, and G and H the delivery-spouts. The body is adapted to be attached to a wall or other upright support. It may be made as an open frame to secure lightness. The casing is made of a suitable shape adapted to inclose the receptacle and the cup. The receptacle is attached to the body in any suitable way—such, for instance, as the strap I, which extends around it and engages by its bent ends with notches in the body. The weight of the receptacle rests on the lug J, projecting outward from the body, and engaging with the shoulder on the bottle. The receptacle is thus supported in position to feed its contents slowly into the cup.

The cover is attached to the body so that it can be readily taken off in any suitable way. In the arrangement shown the lug K engages with the lower cross-bar of the body, and an-

other lug L at the top enters an opening in the cover, the lug being itself elastic or a spring or lock being employed. The cover is provided with any suitably-arranged apertures for the purposes of ventilation and of inspection.

The body is provided with one or more projecting lugs M, which support the cup D. This cup is made in one piece, of glass or other suitable non-corrosive material, open at top and closed at bottom. At one corner the wall N is bent inward to afford room for the receiver O, which is provided with the delivery-tube G. Between the lower open end of the inverted receptacle C and the bottom of the cup D is placed a suitable absorptive material P, such as felt or other suitable fabric, and the liquid disinfectant in the receptacle slowly feeds into the cup as fast as the evaporation allows air to enter the neck of the receptacle. A siphon F is arranged to feed the liquid from the bottom of the cup to the delivery-tubes G or H, as may be desired. The siphon is formed of a piece of wicking and is attached to a flexible strip of metal R, which may be bent in either direction, so as to cause the siphon to feed into either one of the tubes G or H.

The tube G is preferably used where the delivery requires to be drop by drop and the spout H where the feed may be continuous, a pipe being attached to the spout. The inner end of the siphon dips into the liquid in the cup and the outer end at the lower level is placed in one of the spouts. A plate S is placed in the cup, resting on the bottom. The flexible strip R is attached to this plate. A short distance above the plate a piece of perforated metal T is placed below the neck of the receptacle, any suitable absorptive material being interposed, if desired. The perforated metal T turns up at each end, forming wings V. A piece of felt P is attached to the bottom of the strip T and to the inside of the wings. In this way the evaporation of the disinfectant is materially increased.

I claim—

1. The combination with a suitable casing, of a cup mounted in the lower end thereof, an inverted liquid-receptacle opening into said

cup, absorptive material in said cup, a delivery tube and spout adjacent said cup, and a flexible means for conducting the contents of said cup to either said tube or spout as desired, substantially as described.

2. The combination with a suitable casing, of a cup mounted in the lower end thereof, an inverted liquid-receptacle opening into said cup, absorptive material in said cup, a delivery-tube adjacent said cup, a plate mounted in the bottom of said cup, a metallic flexible strip secured to said plate, and a wick supported by said flexible strip for conducting the contents of said cup to said delivery-tube, substantially as described.

3. The combination with the inverted liquid-receptacle, of the cup, the perforated

metal faced with absorptive material and provided with the wings, the receiver and the siphon communicating between the cup and the receiver, as and for the purposes set forth.

4. The combination with an inverted liquid-receptacle, of a cup, a perforated plate, provided with wings, faced with absorptive material, a delivery-tube adjacent said cup, a flexible metallic strip mounted in said cup, and a wick supported by said flexible strip for conducting the contents of said cup to said delivery-tube, substantially as described.

DANIEL N. CALKINS.
